UNITED STATES PATENT OFFICE.

MYRON COSSEY, OF NEW YORK, N. Y., ASSIGNOR TO RELIANCE BALL BEARING DOOR HANGER COMPANY, OF NEW YORK, N. Y., A CORPORATION OF NEW YORK.

DOOR-HANGER.

1,109,202.

Specification of Letters Patent.

Patented Sept. 1, 1914.

Application filed November 21, 1912. Serial No. 732,663.

To all whom it may concern:

Be it known that I, MYRON COSSEY, a citizen of the United States, residing in the borough of Brooklyn of the city of New

5 York, in the county of Kings, in the State of New York, have invented certain new and useful Improvements in Door-Hangers, of which the following is a specification, reference being had to the accompanying drawing, which forms a part hereof.

This invention relates particularly to two- or three-speed hangers for sliding doors in which the several doors or leaves of the compound door are geared together so that 15 the several doors have different speeds and all reach the open or closed position at the same instant.

In door hangers of this type, as usually constructed, the first door travels upon a 20 fixed track while the second door travels upon a track supported by the first door, and so on. The doors are sometimes very heavy and the leverage which is exerted through the hanging of successive doors 25 upon tracks carried by other doors causes lateral pressure and wear upon the balls or rollers through which the doors are supported upon the tracks, with consequent resistance to free movement, deterioration of 30 the hangers, and liability of the balls or rollers to be forced from the track in which they should travel.

It is the object of this invention to provide means whereby each door may be supported upon a stationary track while the 35 relative movement of the several doors is secured through gearing between them arranged substantially as heretofore.

The invention will be more fully explained hereinafter with reference to the accompanying drawing in which the several embodiments of the invention are illustrated and in which—

Figure 1 is a view partly in side elevation and partly in longitudinal section showing a two-speed door hanger constructed in accordance with the invention, the section being on the plane indicated by the line 1—1 of Fig. 2. Fig. 2 is a transverse section on 50 the plane indicated by the line 2—2 of Fig. 1, but on a larger scale. Fig. 3 is a detail view illustrating particularly the construction of the ball carrier.

The door hanger, as delivered to the user, 55 is a unitary structure, with all of its parts

assembled and ready for use. It comprises a bracket or supporting plate *a* adapted to be secured to the wall *b* and to support the other parts of the hanger.

In the construction shown in Figs. 1 and 60 2 the supporting plate *a* has secured thereto a supporting bracket *c* which may consist of a beam *c*¹, a top plate *c*² and a side plate *c*³. A fixed track *d*, for one of the doors, is secured to some part of the supporting structure, such as the plate *a*, and a fixed track *e*, 65 for the other of the two doors is also secured to some part of the supporting structure, such as the plate *c*³. Each rail is grooved, preferably on both its upper and lower 70 sides, as at *d*¹ *d*² and *e*¹ *e*² respectively, to receive balls *f* which are spaced apart by spacers *g* as usual. Carriers *h* and *i*, 75 grooved internally, as at *h*¹ *h*² and *i*¹ *i*² cooperate with the tracks *d* and *e*, through the 80 balls *f* and are provided with hangers *k* and *l* by which the doors *m* and *n* are hung from the carriers *h* and *i* respectively. Each door, as will be observed, thus hangs substantially in the plane of a corresponding 85 fixed track, so that the pressure on the balls is wholly in a vertical plane and there is no lateral pressure which tends to produce excessive wear or lateral displacement of the balls.

In order that the desired relative movement of the several doors may be provided for, one of the doors, as the door *m*, has mounted in connection therewith, through the carrier *h*, on a stud *o* secured to the carrier, a gear *p* which meshes with a fixed rack, as *r*, secured to the supporting structure and with a movable rack, as *s*, secured to the other door through the corresponding carrier *i*. It will therefore be seen that if motion is imparted to the door *m*, for example, the other door *n*, through the described gearing, will be caused to move in the same direction as the door *m*, and at twice the speed, so that both doors reach 100 the open or the closed position at the same instant.

It will be seen that details of construction may be varied to suit convenience in manufacture and different requirements of use 105 and that whether the invention be embodied in one specific form or another, the structure in which it is embodied comprises a fixed rail for each door, from which the door is hung through a suitable carrier; 110

while gearing is provided through which the desired speed of movement of one door with respect to another is secured.

I claim as my invention:

5 A two-speed door hanger comprising a supporting structure consisting of a supporting plate, a beam secured thereto, a depending plate secured to the beam, a plurality of fixed tracks supported by said plates, movable carriers upon said fixed tracks respectively bearing members interposed between the top and bottom edges of said carriers and said fixed tracks, hangers secured to said carriers to support the several doors in substantially the same vertical

plane with the tracks respectively, a stationary rack carried by the supporting beam, a second rack secured to one of said movable carriers, and a gear carried by another of said movable carriers and engaging both of said racks whereby one carrier has a different speed with respect to the other carrier. 20

This specification signed and witnessed this 20th day of November A. D., 1912.

MYRON COSSEY.

Signed in the presence of—

E. M. TAYLOR,

WORTHINGTON CAMPBELL.
